DESIGN FOR A SWEATER

Frank Sheindelman, New York, N. Y.

Application October 6, 1937, Serial No. 71,996

Term of patent 3½ years

To all whom it may concern:

Be it known that I, Frank Sheindelman, a citizen of the United States of America, residing in New York city, in the Borough of Manhattan, county and State of New York, have invented a new, original, and ornamental Design for a Sweater, of which the following is a specification, reference being had to the accompanying drawing, forming part thereof, wherein,

The characteristic feature of my design resides in the combination on the sweater disclosed of the depending front waistband having the ribbed pattern shown.

I claim:

The ornamental design for a sweater, substantially as shown and described.

FRANK SHEINDELMAN.
